APPARATUS FOR CONTINUOUS ELECTROLYSIS OF AQUEOUS SOLUTIONS.

977,125.

Specification of Letters Patent. Patented Nov. 29, 1910.

Application filed November 17, 1909. Serial No. 528,598.

To all whom it may concern:

Be it known that we, ALBERT PIETZSCH, electrical engineer, a subject of the King of Saxony, and resident of Triberg, Grand Duchy of Baden, Germany, and EWALD STEINBUCH, electrical engineer, a citizen of the Swiss Republic, and resident of Montthey, Canton of Valais, Switzerland, have invented new and useful Improvements in Apparatus for Continuous Electrolysis of Aqueous Solutions, of which the following is a full, clear, and exact specification.

In our application for Letters Patent No. 528572 we have described a process for the electrolysis of aqueous solutions, wherein the electrolyte is caused to flow from an upper to a lower electrode and is enriched again by solid salt between the two electrodes, after having been impoverished at the upper electrode, in order that as many ions as possible of the initial electrolyte may travel in the opposite direction to the migrating ions tending to diminish the yield.

The object of the present invention is now to carry out the said process for the electrolysis of aqueous solutions.

In this apparatus a support for solid salt is arranged between the two superposed electrodes and is preferably combined with a device forming a trap for the gases generated at the lower electrode.

In the accompanying drawing Figure 1 shows in vertical section the preferred construction of this apparatus and Fig. 2 represents also in vertical section a somewhat modified construction of the same.

In Fig. 1, *a* is the anode, *b* the cathode which is electrically connected with the iron container *c*. *d* represents two partitions of non-conducting material separating the anode compartment from the cathode compartment and between these partitions there are stretched, on the one hand, a porous fabric *e* which carries the solid salt *f* supplied through the pipes *n* and, on the other hand, a porous fabric *g* closing the bottom of the anode compartment and conducted over non-conducting rods *h* giving the said fabric *g* a zigzag form, so that this latter may serve as a gas trap; *j* is the pipe through which the salt solution is fed to the apparatus and *i* is the overflow through which the formed lye is discharged.

Assuming the apparatus is used for the

electrolysis of a solution of common salt, in order to produce soda lye, the mode of operation will be the following: The salt solution flowing into the electrolytic cell through *j*, after it has become partially impoverished at the anode, flows partly through the salt *f* and partly over this salt, and there is formed over the fabric *g* a layer of concentrated salt solution which passes through the fabric *g* to the cathode compartment and thus prevents migration of the ions formed at the cathode into the anode compartment. The gas (hydrogen) generated at the cathode is caught by the corrugations of the fabric *g* and led away laterally. As the fabric *g* is situated at a certain distance below the fabric *e*, the salt solution enriched with salt below the anode has to traverse a distance of some centimeters before it arrives at the concentrated lye situated directly below the gas trap fabric *g* and in this long path it catches the OH- ions migrating upwardly from the cathode *b*.

In the modified construction of Fig. 2, the solid salt *f* is supplied directly on the porous fabric *l* stretched in zigzag form and closing the bottom of the anode compartment, the said fabric serving consequently simultaneously as salt carrier and as gas trap.

What we claim is:

1. An apparatus for the continuous electrolysis of an aqueous solution, having two superposed electrodes in different compartments, and means to cause the electrolyte to flow from the upper to the lower electrode, in combination with a support of permeable and non-conducting material situated between the two electrodes and designed to receive solid salt, and with means to feed solid salt into the upper electrode compartment in proximity of the said upper electrode substantially as described.

2. An apparatus for the continuous electrolysis of an aqueous solution, having two superposed electrodes in different compartments, and means to cause the electrolyte to flow from the upper to the lower electrode, and a support of permeable and non-conducting material situated between the two electrodes and designed to receive solid salt, in combination with a device forming a trap for the gases generated at the lower electrode and with means to feed solid salt into the upper electrode compartment in proxim-

ity of the said upper electrode, substantially as described.

3. An apparatus for the continuous electrolysis of an aqueous solution, having two superposed electrodes in different compartments, and means to cause the electrolyte to flow from the upper to the lower electrode, in combination with a porous fabric adapted between the two electrodes to receive solid salt, and with means to feed solid salt into the upper electrode compartment in proximity of the said upper electrode, substantially as described.

4. An apparatus for the continuous electrolysis of an aqueous solution having two superposed electrodes in different compartments, and means to cause the electrolyte to flow from the upper to the lower electrode, a porous fabric adapted between the two electrodes to receive solid salt, in combination with a device forming a trap for the gases generated at the lower electrode, and with means to feed solid salt into the upper electrode compartment in proximity of the said upper electrode, substantially as described.

5. An apparatus for the continuous electrolysis of an aqueous solution, having two superposed electrodes in different compartments, and means to cause the electrolyte to flow from the upper to the lower electrode, a porous fabric situated between the two electrodes and designed to receive solid salt and a second substantially horizontal fabric closing the bottom of the compartment of the upper electrode and stretched in zigzag manner in order to form a trap for the gases generated at the lower electrode, substantially as described.

40 6. An apparatus for the continuous elec-

trolysis of an aqueous solution, having two superposed electrodes in different compartments, and means to cause the electrolyte to flow from the upper to the lower electrode, a porous fabric situated between the two electrodes and designed to receive solid salt, means to feed solid salt into the upper cell in proximity of the upper electrode, and a second substantially horizontal fabric closing the bottom of the compartment of the upper electrode and stretched in zigzag manner in order to form a trap for the gases generated at the lower electrode, substantially as described.

7. In an apparatus for the continuous electrolysis of an aqueous solution, the combination of an anode chamber having an anode located therein, a cathode chamber having a cathode located therein, means for causing an electrolyte to continuously flow through said anode chamber and past the anode therein into the cathode chamber and past the cathode therein, means for supporting in a solid condition the salt to be electrolyzed in a position between said anode and cathode chambers and in the direct line of travel of said electrolyte, a permeable fabric provided with ridges to support said solid salt and staggered rods for supporting said fabric in its rigid condition, substantially as described.

In witness whereof we have hereunto signed our names this 5th day of November 1909, in the presence of two subscribing witnesses.

ALBERT PIETZSCH.
EWALD STEINBUCH.
